UNITED STATES PATENT OFFICE

GERHARD FLINTERMANN, OF WEST ORANGE, NEW JERSEY

DESIGN FOR A CONTAINER FOR TOILET ACCESSORIES

Application filed July 1, 1931. Serial No. 40,395. Term of patent 14 years.

To all whom it may concern:

Be it known that I, GERHARD FLINTERMANN, a citizen of the United States, residing at 3 Ridgeview Avenue, West Orange, in the county of Essex and State of New Jersey, have invented a new, original, and ornamental Design for a Container for Toilet Accessories, of which the following is a specification, reference being had to the accompanying drawings, forming part thereof.

I claim:

The ornamental design for a container for toilet accessories, as shown.

GERHARD FLINTERMANN.
